UNITED STATES PATENT OFFICE.

GEORGE A. KERNS, OF VICTORIA, TEXAS.

STIRRUP.

SPECIFICATION forming part of Letters Patent No. 444,298, dated January 6, 1891.

Application filed July 9, 1890. Serial No. 358,220. (No model.)

To all whom it may concern:

Be it known that I, GEORGE A. KERNS, of Victoria, in the county of Victoria and State of Texas, have invented a new and useful 5 Improvement in Stirrups, of which the following is a specification:

My invention relates, generally, to stirrups, and particularly to a new and improved stirrup iron or body, whereby a stirrup of extra- 10 ordinary strength and lightness is produced, and also one that is ornamental and avoids the discomforts of metallic stirrups now in common use.

The object of my invention is to produce a 15 stirrup of the above-noted character that shall be cheap, simple, and durable; and with this object in view my invention consists in certain details of construction and combination of parts shown in the accompanying 20 drawings, and more fully explained herein-after.

In the accompanying drawings, forming a part of this specification, and in which the same numerals of reference indicate the same 25 parts, Figure 1 is a perspective view of my improved stirrup, certain parts being broken away to show the different parts. Fig. 2 is a sectional view of my stirrup, and Fig. 3 is a perspective view of the metallic body portion. 30

In the embodiment of my invention I employ a metallic body portion 10, preferably of thin sheet-steel highly tempered, said portion 35 10 being cut out and struck up by suitable dies, the side bars being gradually tapered toward their upper ends, and the entire body portion is formed at its edges with the outwardly-extending flanges 11. A leather covering 12 is stretched from the interior of 40 the stirrup around the entire metallic body portion 10, said covering being of a width that its edges approach each other (but do not meet) upon the outer face of the metallic body portion 10. The covering-piece 12 is so 45 stretched around the flanges 11 and said flanges are of such width that a groove of considerable depth is left between the flanges when the covering 12 is stretched around the

body portion 10. A leather securing-strip 13 is placed in the groove thus formed, said strip 50 being so shaped as to snugly fit the groove or depression and cover the approaching edges of the covering-piece 12. The strip 13 is secured in place by the rivets 17 passing through the metallic portion 10 and covering-piece 12. 55 By this construction the metallic body is entirely covered and all expense and labor of stitching is avoided.

A roller-block 15 is secured between the upper ends of the bars upon the shaft 17, and 60 an ornamental washer-plate 16 is interposed between the heads of the rivets 14 and the strip 13 and the heads of the shaft 17.

A leather foot-pad 18 may be laced in the usual way around the bottom of the stirrup, 65 as shown. The metallic body, being of thin sheet-steel highly tempered and flanged at edges, is very strong and durable and calculated to resist great pressure. The metallic part is entirely covered with leather without 70 stitching, which renders the article cheap and also ornamental.

Having thus described my invention, what I claim as new is—

As an improved article of manufacture, the 75 herein-described stirrup, consisting of the metallic body portion struck up from sheet metal and formed with outwardly-projecting flanges at its edges, a leather covering-piece stretched around the body portion from the 80 interior of the same, the edges of the covering-piece approaching each other between the flanges on the body portion, a leather securing-piece arranged upon the exterior of the metal body portion between the flanges 85 and covering the approaching edges of the covering-piece, rivets connecting the said parts, a shaft connecting the upper ends of the body portion, and the foot-pad laced around the lower part of the same, all of said 90 parts being constructed and arranged substantially as shown and described.

GEORGE A. KERNS.
